Des. 236,985
Patented Sept. 30, 1975

236,985

DYNAMOELECTRIC MACHINE

Frederick W. Baumann, Scotia, N.Y., assignor to General
Electric Company, Schenectady, N.Y.

Filed Feb. 5, 1973, Ser. No. 329,913

Term of patent 14 years

Int. Cl. D13—01

U.S. Cl. D26—5 A

FIG.1

FIG.2

FIG.3

FIG.4

FIG.5

FIG.6

FIG. 1 is a perspective view of a dynamoelectric machine showing my new design;

FIG. 2 is an end elevational view thereof of the end opposite to that shown in FIG. 1;

FIG. 3 is a top plan view thereof;

FIG. 4 is a side elevational view thereof;

FIG. 5 is a side elevational view thereof opposite to that shown in FIG. 4; and

FIG. 6 is a bottom plan view thereof.

The rod illustrated has been broken away in FIGS. 3, 4, 5 and 6 for convenience of illustration.

I claim:

The ornamental design for a dynamoelectric machine, as shown and described.
